UNITED STATES PATENT OFFICE

166,487

MOP

William E. Parker, Warren, Ohio

Application April 14, 1951, Serial No. 14,835

Term of patent 14 years

(Cl. D9—2)

To all whom it may concern:

Be it known that I, William E. Parker, a citizen of the United States, residing at Warren, in the county of Trumbull and the State of Ohio, have invented a new, original, and ornamental Design for a Mop, of which the following is a specification, reference being had to the accompanying drawing, forming part thereof:

Figure 1 is a perspective view of a mop, showing my new design.

Figure 2 is a central longitudinal sectional view of the mop shown in Figure 1.

Figure 3 is a view similar to Figure 2 but showing parts in different relation, and

Figure 4 is a transverse sectional view corresponding generally to the line 4—4 of Figure 2.

The dominant features of my design reside in the portions shown in full lines.

I claim:

The ornamental design for a mop, substantially as shown and described.

WILLIAM E. PARKER.
